KINGSTON GODDARD, OF RICHMOND, NEW YORK.

Letters Patent No. 74,817, dated February 25, 1868.

IMPROVED THILL-COUPING.

The Schedule referred to in these Letters Patent and making part of the same.

TO ALL WHOM IT MAY CONCERN:

Be it known that I, KINGSTON GODDARD, of Richmond, in the county of Richmond, and State of New York, have invented a new and improved Thill-Coupling; and I do hereby declare that the following is a full, clear, and exact description thereof, which will enable those skilled in the art to make and use the same, reference being had to the accompanying drawings forming part of this specification.

This invention relates to a new and improved means for connecting the thills of vehicles to their front axles; and it has for its object the attachment of the thills in such a manner that the latter may be connected to and detached from the axle with the greatest facility, and when attached, with the horse harnessed before the vehicle, casual detachment of the thills is rendered impossible. In the accompanying sheet of drawings—

Figure 1 is a side sectional view of my invention, taken in the line xx , fig. 2.

Figure 2 is a plan or top view of the same.

Similar letters of reference indicate corresponding parts.

A represents a portion of the front axle of a wheeled vehicle, and B represents a clip, which encompasses the same, and may be constructed in the usual or in any proper manner. C represents the thill-iron, attached to the rear end of the thill as usual; and having at its outer end a socket, D, formed by bending down the thill-iron, so as to leave a shoulder, a , and bending the outer end of the iron upward parallel with a , as shown at b , and then bending the upper end of b over inward toward the axle, as shown at c , having the end c notched, so as to receive a projection, d , on the clip when the thill is attached thereto. The bent end, c , laps over the rear end of the bottom plate e of the clip, as shown clearly in fig. 1, and holds the thill-iron up to the clip, while the notched bent end c prevents any lateral movement of the thill-iron; the shoulder a bearing against the front end of plate e when the horse is backed. When the horse is harnessed to the vehicle, and the thills held up by the lugs of the harness, the thill-iron cannot become casually detached, but when the horse is unharnessed, and the thills let down, the thill-irons may be detached from the clip with the greatest facility.

Having thus described my invention, I claim as new, and desire to secure by Letters Patent—

The bending or forming of the outer end of the thill-iron, substantially as shown and described, so as to be capable of being fitted to the under side of the clip, in the manner as and for the purpose set forth.

KINGSTON GODDARD.
